UNITED STATES PATENT OFFICE.

ROBERT ROSS ZELL, OF BIRMINGHAM, ALABAMA, ASSIGNOR TO ZELL AEROMOBILE COMPANY, OF BIRMINGHAM, ALABAMA, A CORPORATION OF ARIZONA.

AIRSHIP.

1,033,510.

Specification of Letters Patent. Patented July 23, 1912.

Application filed March 17, 1911. Serial No. 615,137.

To all whom it may concern:

Be it known that I, ROBERT ROSS ZELL, a citizen of the United States of America, residing at the city of Birmingham, State of Alabama, have invented certain new and useful Improvements in Airships, of which the following is a specification.

This invention relates to airships of the heavier than air type. Vehicles of this nature are subject to numerous defects, the principal of which are a tendency to capsize in turning, whereby the supporting planes approach the vertical and the machine falls; a greater or less tendency to descend rapidly when the motor stops; and the extreme difficulty with which they may be gotten into the air for flight.

The object of this invention is to overcome these and other defects, and produce a new and improved airship of the heavier than air type which can be guided on the most circuitous course without the danger of capsizing, which is so constructed that if the motor stops by accident or otherwise, the machine will descend gradually to the earth, and which is capable of rising from the earth directly into the air without being propelled along the ground to gain the necessary speed to bring its lifting planes into operation as is the case with all the heavier than airships or aeroplanes now in use.

One of the most apparent defects, common to all heavier than air machines, is one to which I refer, that of getting them to mount. They must be propelled along the ground and their speed accelerated until the vertical component of the resistance of the air on the planes becomes equal to or greater than the weight of the machine. To eliminate the necessity for generating the lifting force by acceleration in a horizontal direction, I make the propeller adjustable along a vertical arc so that its axis may be deflected downward at any desired angle with the horizontal. To this same end I find it desirable to pivot the lifting planes so that they may be adjusted about a transverse axis which is preferably through their center of effort. To cause the machine to rise directly off the ground, I have merely to adjust the lifting planes

to the proper angle, swing the propeller downward and give it rotation. These features are described, shown and claimed in a co-pending application, Serial No. 703,645.

To keep the machine on an even keel in making curves, etc., I provide separate controlling means for the planes on each side of the machine, so that they may be rotated about the transverse axis on which they are pivoted, to give the planes on one side a different angle of incidence from those on the other side. In making changes of direction and rounding curves, the outside plane can be tipped downward and the inside plane upward. Thus the tendency to tip, which ordinarily throws the outside of the machine up and the inside down, is counteracted. It will be apparent that in making such turns, an appreciable amount of centrifugal force is brought to bear on the machine, and that to maintain the machine on an even keel, would reduce its resistance to such centrifugal force. To prevent deflection of the machine from its course, and for other purposes, as steering, I make the propeller adjustable laterally as well as vertically, so that in making curves, it may be swung outward to counteract the centrifugal tendency. It thus becomes necessary to adjust the propeller both vertically and laterally, and so universally. A practical difficulty to be overcome in providing such adjustment of the propeller, is that with the high speed of rotation necessary for this kind of work, jointed shafts are ineffective and short-lived.

An important feature of my invention is a means for mounting and supporting the propeller so that it may be universally adjusted, and at the same time directly connected to the motor so that universal adjustment can be provided without interfering with the regularity and certainty of operation of the propelling gear. To this end I mount the propeller and motor on horizontal trunnions transverse to the direction of travel of the machine, and passing through the center of gravity of the combined mass of the motor, propeller and connections. These trunnions are journaled in a movable frame which is itself mounted on vertical pivots. Thus the engine and

propeller may be swung in a vertical arc about the trunnion bearings in the movable frame, and the frame, engine, propeller and all may be rotated about the vertical pivots which are journaled in the main frame. A vertical arcuate guide for the propeller is secured to the movable frame carrying the trunnion bearings; a horizontal arcuate guide is carried by the main frame; the vertical guide is suspended from this horizontal guide, and it travels thereon. The vertical guide is concentric with the trunnion bearings and the horizontal guide with the bearings of the vertical pivot.

To give the machine added stability in its normal operation, I have placed the main frame, with its center of gravity, below the center of effort of the lifting planes which I have described as pivoted on a transverse axis, so that the frame is suspended pendulum-wise from the center of effort of the planes. By this arrangement I establish a tendency in the machine to right itself, whenever the center of gravity is deflected from a vertical line, through the center of effort of the planes.

A preferred embodiment of my invention is shown in the accompanying drawings, of which—

Figure 1 is a side elevation of the machine, certain parts being removed for convenience in illustration. Fig. 2 is a top plan of the machine, the parachute and stationary triplane being removed. Fig. 3 is a front elevation of the machine. Fig. 4 shows the engine, frame, propeller, clutch and vertical circular guide in plan, the movable frame carrying the engine being cross-sectioned.

Referring to the drawings, the machine, as shown consists of a main frame or fuselage "1," the top "2" of which is concave downward to form a parachute. Mounted within and beneath the parachute is a stationary triplane "3." A shaft "4" shown as broken away to disclose the controller ropes, is mounted in the fuselage, and extends transversely thereof near its longitudinal center. Journaled on this shaft at each side of the fuselage, the shaft passing through or near its center of area, is lifting plane "5." In the embodiment of my invention illustrated, these lifting planes are shown as triplanes. Secured one to each of the triplane "5," concentric with the shaft "4," are toothed gears "6." A gear "7" on shaft "7" parallel to the shaft "4" co-operates with each of the toothed gears "6." Mounted on the shaft "7" of each gear "7" is a gear "8" engaged by a chain "9" which leads forward over gear "10" on a transverse shaft "11." Each of the shafts "11" carries a hand-wheel "12," one of which is on each side of the pilot's seat "13." It will thus be apparent that the lifting planes may be

rotated independently of each other relatively to the main frame about a transverse axis passing through their centers, and as this axis is above the center of gravity of the main frame, the latter is in effect hung as a pendulum from the centers of effort of the lifting planes.

The motor "14" with the propeller "15" and its shaft "16," are mounted upon trunnions "17" which pass horizontally through the center of gravity of the combined masses of the motor, propeller, shaft, and connections. The trunnions "17" are journaled in bearings "18," carried by a frame "19" which is itself mounted on vertical pivots "20" on the main frame to swing laterally relatively thereto. The frame "19" carries a vertical arcuate guide "21" secured thereto by means of braces "22." The guide is concentric with the journal "18" and serves as a track for the propeller bearing "23." Concentric with the vertical pivot "20" and secured to the main frame, is a horizontal arcuate guide or track "24." This track is engaged by a roller "25" carried by the vertical guide.

The operation of the universal adjustment of the propeller will be apparent. As the engine and propeller are swung laterally the vertical guide moves from side to side over the horizontal track. As they are swung vertically, the propeller bearing moves up and down in the vertical guide.

The position of the propeller is controlled by means of hand-wheels "26" and "27" in front of the pilot's seat, one at each hand. Connected to each wheel is a drum "28" over which run two or three turns of a rope drive. The rope "29" which engages the drum "28" of the hand-wheel "26," is connected to each side of the upright guide "21," passes over idlers "30," one at each side of the frame, and then forward to guide "31" and to the drum "28." It will be apparent that by operation of the hand-wheel "26," the vertical guide "20" can be moved back and forth on the track "24." At the same time the propeller will be moved from side to side, the propeller and engine being oscillated about the vertical axis through the center of gravity of their combined masses.

The drive rope "32" attached to the drum "28" of the hand-wheel "27," passes over the pulley "33" on the vertical guide. The rope "32" serves to adjust the propeller to any desired position.

For the purpose of controlling the machine and steering it laterally, I provide wing planes "35" one on each side of the rear of the machine, mounted on vertical pivots. The position of these planes is controlled by means of drive ropes "36" running over pulleys "37" and "38," the pulleys "37" being on the shafts "39" which

carry the wing planes. The ropes "36" pass over the reel "40" controlled by hand-wheel "41" in front of the pilot.

In starting the machine from the ground, 5 the preferred method of operation is to swing one wing plane outward on the side on which it is mounted so as to cause the machine to take a course toward the side of the deflected plane. The lifting planes are 10 then inclined to a similar angle, their forward edges being lifted, the propeller is thrown down and started, and the machine rises in a spiral course lifted by the inclined planes and propeller and deflected by the 15 wing plane.

As shown, the machine is provided with a foreplane "43" pivoted at "44," and adjusted by means of drive rope "45" on drum "46" controlled by hand-wheel "47," and a 20 tailplane "48" pivoted at "49," and preferably formed with a quadrant "50" engaging a pinion "51" operated by drive rope "52" running over the drum "46." These are for partially controlling the 25 course of the machine in a vertical plane and either are supplementary to the propeller and lifting planes.

When the machine alights, it ordinarily has a certain amount of forward velocity 30 which must be gradually reduced. It is also difficult to prevent some slight shock on landing. For these purposes I have provided a skid "53" of an improved type. The skid consists of a pair of runners "56" 35 provided at each extremity with loops or links "57". Overlying each runner is a spring "58" which passes through the loops and is secured centrally to the bottom of the main frame at "59". A double bow-spring 40 "60" on each side of the skid, between the runner and the spring "58", is pivoted centrally of each bow at the bottom to the runner at "61", and at the top to the main frame at "62". The members of the double 45 bow "60" are pivotally connected at their extremities at "62", and these pivots, as shown, are connected to the frame by chains "64". The pivots "63" also serve as the 50 journals for wheels "65" which engage the earth when the skid is under abnormal pressure.

The propeller shaft "16" is shown as provided with a clutch "67" for throwing the motor into and out of gear with the propeller. This clutch is controlled by a lever 55 "68", operated by a treadle "69", connected thereto by a rod "70".

The operation of the air ship will be apparent from the description of its various 60 features.

I have thus set forth in detail a single embodiment of my invention in order that its nature and operation may be fully understood. However, the form and numbers 65 of the parts may be widely varied, different

non-essential features may be dispensed with or others substituted for them. The specific terms are used in their descriptive rather than their limiting sense, and the scope of the invention is defined in the 70 claims.

I claim—

1. In an airship, a propeller and driving gear therefor, the propeller and driving gear being universally adjustable about the 75 center of gravity of their combined mass, a horizontal arcuate guide on the frame, and an upright arcuate guide for the propeller, suspended from the horizontal guide and traveling thereon, both guides being concentric with the center of gravity of the propeller and driving gear.

2. In an airship in combination a propeller and driving gear therefor, the propeller being universally adjustable, a horizontal 85 arcuate guide and a vertical arcuate guide for the propeller, the vertical guide suspended from and traveling on the horizontal guide.

3. In an airship in combination a main 90 frame, a propeller, a motor, a motor frame, horizontal trunnions supporting the motor and having bearings in the motor frame, vertical pivots supporting the motor frame on the main frame, a horizontal arcuate guide 95 concentric with the vertical pivots and secured to the main frame, a vertical arcuate guide concentric with the trunnions and suspended from and traveling on the horizontal guide.

4. In an airship in combination a main 100 frame, a propeller, a motor, a motor frame mounted to swing in a horizontal plane relatively to the main frame, the motor being mounted to swing in a vertical plane 105 relatively to the motor frame, a horizontal arcuate guide secured to the main frame concentric with the axis about which the motor frame swings, a vertical arcuate guide for the propeller concentric with the trunnions and secured to the motor frame suspended from and traveling on the horizontal guide.

5. In an airship in combination a main 110 frame, a propeller, a motor, a motor frame mounted to swing in a horizontal plane relatively to the main frame, the motor mounted in its frame to swing in a vertical plane relatively thereto, a horizontal arcuate guide secured to the main frame concentric with the axis about which the motor frame swings, a vertical arcuate guide for the propeller concentric with the trunnion secured to the motor frame, suspended from and traveling on the horizontal guide, the 115 axes of the trunnions and the motor frame passing near the center of gravity of the combined masses of the motor and propeller.

6. In an aeroplane, a propeller, a motor, a driving shaft connecting the motor and 120

propeller, universally adjustable means supporting the motor and propeller, a horizontal guide on the frame, and an upright arcuate guide for the propeller traveling on 5 the horizontal guide.

7. In an airship, in combination a main frame, a propeller, a motor, a motor frame, horizontal trunnions supporting the motor and having bearings in the motor frame, 10 vertical pivots connecting the motor frame to the main frame, a horizontal guide se-

cured to the main frame, a vertical arcuate guide for the propeller on the motor frame concentric with the trunnions and traveling on the horizontal guide.

15

Signed by me at city of Birmingham, State of Alabama, this 10th day of February 1911.
